(57) **CLAIM**

The ornamental design for a misting and watering device, as shown and described.

DESCRIPTION

FIG. 1 is a perspective view of the pole mister showing our new design;

FIG. 2 is a front view thereof;

FIG. 3 is a side view thereof;

FIG. 4 is a rear view thereof;

FIG. 5 is a side view thereof;

FIG. 6 is a top view thereof; and,

FIG. 7 is a bottom view thereof.

The dotted lines shown in the drawings do not make up any part of the claimed design.

The claimed design is shown fragmented to indicate non-specified length.
